(57) **CLAIM**

The ornamental design for a surface configuration of a vehicle, toy and/or other replicas, as shown and described.

DESCRIPTION

This Application is related to the following co-pending applications, of the inventor, filed on even date here with: Application Ser. No. 29/189,173, entitled "Surface Configuration of a Rear Door for a Vehicle"; Application Ser. No. 29/189,174, entitled "Surface Configuration of a Front Bumper for a Vehicle"; and Application Ser. No. 29/189,175, entitled "Roof Antenna for a Vehicle".

FIG. 1 is a front view of a surface configuration of a vehicle, toy and/or other replicas according to my novel design;

FIG. 2 is a left, front perspective view of the surface configuration of a vehicle, toy and/or other replicas according to my novel design, the right, front perspective view being mirror symmetrical;

FIG. 3 is a left side view of the surface configuration of a vehicle, toy and/or other replicas according to my novel design;

FIG. 4 is a right side view of the surface configuration of a vehicle, toy and/or other replicas according to my novel design;

FIG. 5 is a rear view of the surface configuration of a vehicle, toy and/or other replicas according to my novel design;

FIG. 6 is a left, rear perspective view of the surface configuration of a vehicle, toy and/or other replicas according to my novel design, the right, rear perspective view being mirror symmetrical; and,

FIG. 7 is a top view of the surface configuration of a vehicle, toy and/or other replicas according to my novel design.

The broken lines are for illustrative purposes only and form no part of the claimed design.
